UNITED STATES PATENT OFFICE

2,548,041

WINDOW APPLIANCE

Albert H. Morse, Beverly, Mass.

Application March 10, 1949, Serial No. 80,689

1 Claim. (Cl. 160—23)

1

My present invention relates to an improved window appliance and more particularly to a housing adapted for mounting above the upper window sash together with a shade, a screen, and a storm sheet and their rollers, and means for sealing the sides and bottom of the screen and/or storm sheet when alternatively used.

According to my invention I employ a pair of retainers for insertion in the upper corners of the window frame to receive end brackets of the housing and in the housing I use three conventional shade rollers one each for the shade, the flexible screen and the flexible storm sheet. A guide frame on the sides of the window frame has a pivotally mounted strip which may be closed to press the extended screen or sheet against the guide frame.

In the accompanying drawings I have illustrated one complete example of the physical embodiment of my invention according to the best mode I have thus far devised, but it will be understood that various changes and alterations may be made in the exemplified structure within the scope of the appended claim.

In the drawings:

Fig. 1 is a perspective view of the device of my invention partially in section for clarity of observation.

Fig. 2 is an enlarged detail view in perspective partially broken away showing the upper structure.

Fig. 3 is a similar view showing the lower structure.

Fig. 4 is a transverse horizontal sectional view through the window frame and the guide.

Fig. 5 is a partial perspective view showing the sealing construction and pull strip on the lower end of the screen and sheet.

Fig. 6 is a vertical transverse sectional view through the housing.

Fig. 7 is an elevational view of one retainer.

Fig. 8 is an elevational view of one housing bracket.

Fig. 9 is a sectional view at line 9—9 of Fig. 7.

Fig. 10 is a sectional view at line 10—10 of Fig. 8.

Fig. 11 is a sectional view at line 11—11 of Fig. 5.

Fig. 12 is an elevational view of a modified retainer and bracket.

Fig. 13 is a sectional view at line 13—13 of Fig. 12.

Fig. 14 is a sectional view at line 14—14 of Fig. 12.

Referring now to the drawings, I have illus-

2

trated a window including the side trim panels 2, lower sash 4, and frame 6. The usual sill 8 is illustrated as is the top trim 10.

A pair of retainers 12 have edge flanges 14 and these retainers are suitably secured in the window frame at the opposite upper corners thereof. The lower flanges are notched to allow the V-ends 16 of springs 18 to extend therethrough and the springs are secured to the flanges as at 10 20.

The housing 22 is rectangular in cross-section and has in the bottom wall an elongated slot 24, and the housing is closed at each end by brackets 26 having a peripheral flange 28 notched at 30. 15 These brackets with the housing therebetween may be slid between the flanges 14 of retainers 12 and the V-ends 16 will engage the notches 30.

The brackets have a series of raised disks 32, one of which has a central round aperture 34, and the others have rectangular apertures 36 to receive the usual round or rectangular shade roller ends.

The rollers 38, 40 and 42 have wound thereon respectively an opaque window shade 44, a plastic screen 46, and a solid transparent plastic sheet 48. Each of the sheets 44, 46, and 48 has a pull bar 50 bent upon itself and suitably secured to its sheet, and in addition the sheet 48 has attached to its pull bar, a layer 52 of felt or other suitable sealing material.

Obviously from the above description the shade 44 and either the screen 46 or the sheet 48 may be lowered as weather and other conditions may require.

35 In order to seal the edges of the screen 46 or sheet 48 I employ a U-shaped guide having a base 54 secured as by screws 56 to the panels 2 one leg 58 being longer than the other leg 60. The leg 60 has spaced hinge loops 62 for pintle 64,

40 and adapted for co-action therewith I provide a hinge plate 66 having hinge loops 68 and bent at 70 and then upon itself at 72 to form pressure plate or foot 74 which has a sealing strip 76.

The leg 58 is positioned so that the screen 46 or sheet 48 will lie vertically proximate thereto and when the screen or sheet is lowered, the plate 66 may be swung in so that the pressure foot 74 and strip 76 will press the screen or sheet against leg 58.

50 The guide terminates short of the sill and normally before the hinge plate is swung in the pull bar 50 of the screen or sheet is pressed against the sill parallel thereto and when the hinge plate is pivoted inwardly the screen or sheet is locked in extended position and at the same time the

pull bar is pressed against the sill due to the snug fit between the lower edge of the hinge plate and the pull bar.

In Figs 12 through 14 I have illustrated a modified form of retainer and bracket for the housing 22 wherein the retainer 78 has top and bottom flanges 80 and on the inner wall spaced from the lower flange I use a spring clip 82 secured as by rivet 84 and formed with two convex extensions 86.

The bracket 88 has an annular flange 90 and a central cruciform platform 92 having in each bracket two round apertures 94 and one rectangular aperture 96. As the bracket is slid into the retainer the spring clip will engage in the vertical arm of the cruciform platform to retain the bracket and housing in the window frame.

By the use of my invention the need for demountable window screens and storm sash is eliminated and in a single attachment or appliance I provide a shade, a screen and a storm sheet selectively useable and stored easily in the housing when not in use.

Having thus fully described my invention what I claim as new and desire to secure by Letters Patent is:

A window attachment comprising a housing, means supporting the housing in a window frame, a shade roller in the housing, window covering material on the roller, a vertical guide plate on the window frame, and a hinged pressure plate having a pressure foot formed thereon and a sealing strip on the foot which is adapted to bear against the material to seal the same against the guide plate.
